UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPLING MECHANISM.

Application filed October 13, 1925. Serial No. 62,263.

The invention relates to car coupling mechanism employed for the purpose of connecting an automatic coupler of the vertical plane type to a car equipped with a drawhook or the like. Coupling mechanisms of such a character are generally known as transition couplings.

The principal object of the invention is to provide a simple, rugged and easily manipulated coupling device of the character indicated in which the clearances between the parts are amply sufficient to prevent breakage or injury of the mechanism during buffing operations.

15 A primary feature of the invention, generally stated, consists in employing a forwardly curved loop member for connecting a drawhook to a coupler of the type employing a rotatable knuckle, the loop member being 20 pivotally mounted on the coupler head and being connected to a link device adapted to cooperate with a drawhook and the coupler head having a bollard for engaging the loop member to prevent forward rotation of the 25 latter under the influence of draft forces applied to the mechanism.

30 A further feature of the invention consists in pivoting a loop member upon the guard arm side of the coupler head and in providing the coupler head on its knuckle side with a bollard for cooperating with the loop member to prevent forward rotation of the latter.

35 A still further feature of the invention consists in undercutting the rear face of the bollard which cooperates with the pivoted loop member, whereby accidental upward movement of the loop member is prevented when the mechanism is in service.

40 Other features of the invention relating to advantageous forms and relations of parts will hereinafter appear.

In the drawings

45 Figure 1 is a plan view of a coupler, transition gear and drawhook, the parts being connected and in pulling relation.

Figure 2 is a side elevational view of the mechanism, the parts being in pulling position.

50 Figure 3 is a view partly in section and partly in front elevation, showing the relation of the transition gear to the coupler.

Figure 4 is a detailed sectional view on the line 4—4, Figure 1.

In the preferred embodiment of the invention illustrated in the drawings, 1 is an automatic coupler whose stem is attached to the car by suitable draft rigging appliances (not shown) in any usual or desired manner. Rotatably mounted upon the head 2 of the coupler by a knuckle pin 3 in the usual manner is a knuckle 4 having a tail 5. A suitable lock 6 movably mounted on the coupler head normally prevents outward or uncoupling rotation of the knuckle by cooperating with the tail 5 of the latter.

Pivottally mounted upon the coupler head 2 is a loop member 7 provided with a downwardly extending post 8 forming a pivot for said loop member. For receiving the pivot post 8 the coupler head is provided with a suitable cylindrical recess or opening 9 and to prevent forward rotation of the loop member 7 when the latter is subjected to pulling forces in service said head is fashioned with an upwardly extending bollard 10 adapted to engage the loop member at a point some distance from the pivot post 8. It is most advantageous to locate the post receiving opening 9 on the guard arm side of 50 the coupler head and to position the bollard on the knuckle side of the coupler head immediately adjacent the knuckle pin 3, the bollard being somewhat in advance of the pivotal axis of the loop member.

55 The loop member 7 is preferably made of round bar stock. Between its pivotal axis and point of engagement with the bollard 10 it is curved so as to be spaced forwardly from the buffing face 11 of the coupler head, the center of curvature of said curved portion being in spaced relation to the longitudinal axis of the coupler when the parts are in normal operating relation. By this means the draft forces applied to the loop member 7 serve to 95 swing the coupler to one side so as to move the outer end of the knuckle 4 away from the link device by which the loop member is connected to the drawhook 12 of an adjacent car. The free end 13 of the loop member is preferably convexly curved rearwardly so as to hook around the bollard 10 to some extent. The cooperating face of the bollard is similarly curved and is undercut as indicated at 100

14. By thus constructing the bollard so that it overlaps a portion of the loop member 7 the latter is prevented from accidentally moving upward when the mechanism is in service.
- 5 The pivot post 8 of the loop member is preferably vertical and may advantageously extend entirely through the coupler head 2. Its length is such as to permit the vertical movements necessary to enable the loop member to be moved to and from operative position. A cotter 15 passing through the lower end of the pivot post 8 may be conveniently employed for retaining the loop member 7 in assembled relation to the coupler head.

Adjacent the opening 9 for receiving the pivot post of the loop member the coupler head is formed with a depression or notch 16 into which the loop member descends 20 when it is swung around to the guard arm side of the coupler. By this means the loop 7 and transition coupling devices carried thereby are prevented from accidentally swinging forward when not in use.

- 25 The loop member 7 is movably attached to a plurality of connected link members, 17 and 18 respectively, the former being adapted to cooperate with a draft hook 12 and the latter preferably being formed as 30 an eye-bar connected at its forward end to the link 17 and attached at its rear end to the loop member. The openings 19 in the I-bar may advantageously be flared so as to provide for ample flexibility of the connections between the parts without undue increase in the size of said openings.

When the transition coupling devices are in use the knuckle 4 is prevented from accidentally rotating inwardly to a position in 40 which it would interfere with the link members of the transition device. An advantageous means which is employed for this purpose may consist of a coil spring 20 which encircles the lower end of the knuckle 45 pin 3, one end of said spring extending into a perforated lug 21 at the lower end of the pulling lugs of the knuckle 4 and the other end similarly cooperating with a perforated lug 22 on the underside of the coupler head.

- 50 Any suitable means may be employed for actuating the coupler lock. The means illustrated in the drawings are those preferably used for actuating the lock when the latter is provided with a downwardly extending portion or lifter, and consist of the well known bell crank lever 23 which is attached by a pivot 24 to perforated lugs 25 formed on the underside of the coupler head. One of the arms 26 of the lever 23 enters 60 the eye or opening 27 in the lower end of the lock lifter 6, while the other arm of the lifter is formed with an opening 28 permitting the attachment of a pull rod in the usual manner.

65 When the transition gear is not to be

used the loop member 7 is rotated rearwardly sufficiently far to withdraw its free end from beneath the overhanging upper end of the bollard 10, after which it may be raised and swung in the opposite direction back over the guard arm of the coupler head until it settles in the retaining notch or depression 16 of the head adjacent the pivot post 8. When the loop member is in this position the intermediate I-bar 18 and the link 17 hang downwardly at the side of the coupler.

I claim:

1. Car coupling mechanism comprising a coupler head, a knuckle rotatably mounted 80 on said head, and a lock for said knuckle, in combination with means adapted to connect said coupler when the knuckle of the latter is in open position to a coupling device of a different type, said means including a member pivotally mounted on said head in spaced relation to the longitudinal axis of the latter so as to rotate on a substantially vertical axis, and means movably connected to said pivoted member for connecting the latter to the said coupling device of different type, said coupler head being provided with means for limiting forward rotation of said pivoted member.

2. Car coupling mechanism comprising a coupler involving a coupler head, a knuckle rotatably mounted on said head, and a lock for said knuckle, in combination with means adapted to connect said coupler to a drawhook, said means including a member pivotally mounted upon the coupler head at one side of the latter and having a forwardly extending loop portion adapted to swing in a substantially horizontal plane, and a link device movably connected to said loop and adapted to cooperate with a drawhook, said coupler head being provided with a bollard for engaging said pivoted member to prevent forward rotation of the latter when the mechanism is subjected to draft strains.

3. Car coupling mechanism adapted to connect a drawhook or the like to a car coupler involving a coupler head, a knuckle rotatably mounted on said head and a lock for said knuckle, said mechanism including 115 a member pivotally mounted on the guard arm side of the coupler head and having a bar portion extending from the pivotal point of said member toward the knuckle side of said head, and a link device movably connected to said bar portion and adapted to cooperate with a drawhook, said coupler head having means mounted thereon and projecting upwardly therefrom for preventing forward rotation of said bar portion 120 when the mechanism is subjected to draft strains.

4. Car coupling mechanism comprising a coupler involving a coupler head, a knuckle 125 rotatably mounted on said head, and a lock 130

for said knuckle, in combination with means adapted to connect said coupler to a drawhook, said means including a member formed with a pivot post, and having a forwardly curved loop portion, said head having a pivot opening for receiving said post and also being provided with a bollard for cooperating with said loop portion to resist draft strains imparted to the latter, and a link device movably connected to said loop portion and adapted to cooperatively engage a drawhook.

5. Car coupling mechanism comprising a coupler head, a knuckle rotatably mounted on said head, and a lock for said knuckle, in combination with means adapted to connect said coupler to a drawhook, said means including a member pivotally mounted on said head in spaced relation to the longitudinal axis of the latter, said head being provided adjacent the axis of rotation of said knuckle with a bollard adapted to engage said pivotally mounted member to limit rotation of the latter.

10. Car coupling mechanism comprising a coupler involving a coupler head, a knuckle rotatably mounted on said head, and a lock for said knuckle, in combination with means adapted to connect said coupler to a drawhook, said means including a member pivotally mounted on the guard arm side of the coupler head and extending toward the knuckle side of said head, and a link device movably connected to said pivotally mounted member, said head being provided adjacent the axis of rotation of said knuckle with a bollard whose rear face is undercut to receive said pivotally mounted member.

15. Car coupling mechanism comprising a coupler involving a coupler head, a knuckle rotatably mounted on said head, and a lock for said knuckle, in combination with means adapted to connect said coupler to a drawhook, said means including a forwardly curved loop member having at one end a downwardly extending pivot post, said coupler head being formed with a recess for receiving said pivot post and having in advance of said recess and on the opposite side of said head a bollard for engaging said loop member to prevent forward rotation of the latter when the mechanism is subjected to draft strains.

20. Car coupling mechanism comprising a coupler involving a coupler head, a knuckle rotatably mounted on said head, and a lock

for said knuckle, in combination with means adapted to connect said coupler to a drawhook, said means including a forwardly curved loop member movably mounted on the coupler head so as to be capable of sliding vertically and rotating horizontally, and a link device movably connected to said loop member and adapted to cooperate with a drawhook, said coupler head being provided with a bollard constituting means for preventing forward rotation of the loop member when the latter is subjected to draft strains.

25. Car coupling mechanism comprising a coupler involving a coupler head, a knuckle rotatably mounted on said head, and a lock for said knuckle, in combination with means adapted to connect said coupler to a drawhook, said means including a loop member having a downwardly extending pivot post whereby it is mounted on said head so as to be also capable of sliding movement with respect to the latter, means for preventing forward rotation of said loop member when the latter is subjected to draft strains, and a link device movably connected to said loop member and adapted to cooperate with a drawhook, said coupler head being formed with a pivot opening for receiving said pivot post and being provided with a depression for receiving said loop member to maintain the latter in inoperative position.

30. Car coupling mechanism comprising a coupler involving a coupler head, a knuckle rotatably mounted on said head, and a lock for said knuckle, in combination with means adapted to connect said coupler to a drawhook, said means including a forwardly curved loop member having a downwardly extending pivot post and a link device movably connected to said loop member and adapted to cooperate with a drawhook, said link device involving a plurality of movably connected members, said coupler head being provided on the guard arm side thereof with a pivot opening for receiving said pivot post and being provided in spaced relation to said pivot opening with a bollard adapted to engage said loop member to prevent forward rotation of the latter when draft strains are applied thereto, said bollard being undercut on its rear face so as to permit it to extend over a portion of said loop member.

35. In testimony whereof I affix my signature.
WILLIAM KELSO.
